UNITED STATES PATENT OFFICE.

FRANK E. VAN DOORN, OF QUINCY, ILLINOIS.

SHELL FOR DEPOSIT-BOXES.

1,323,560.

Specification of Letters Patent.

Patented Dec. 2, 1919.

Application filed July 14, 1919. Serial No. 310,550.

To all whom it may concern:

Be it known that I, FRANK E. VAN DOORN, a citizen of the United States, residing at Quincy, in the county of Adams and State 5 of Illinois, have invented certain new and useful Improvements in Shells for Deposit- Boxes, of which the following is a specification, reference being had to the accompanying drawings.

- 10 This invention relates to certain improvements in shells for deposit boxes such as employed in banks or the like, and it is an object of the invention to provide a novel and improved device of this general character including a nest in which the drawers or boxes are slidably arranged and wherein the parts comprised in the shell are assembled in a manner eliminating the use of rivets or kindred holding members.
- 15 It is also an object of the invention to provide a novel and improved device of this general character wherein the shell and nests are constructed in a manner which assures accuracy in the fitting of the doors and the 20 desired holding of the drawers or boxes and whereby the assembled device is of pronounced strength.

Another object of the invention is to provide a novel and improved device of this 25 general character wherein the shell is formed of metal with the joints thereof welded and wherein the nests within the shell are formed by interlocking vertically arranged and horizontally disposed sheets, welded, and preferably spot welded, to the shell so that the assembled parts constitute substantially an integral structure. An additional object of the invention is to provide a device of this general character including 30 novel and improved means for assembling the sheets within the shell to produce the required nests for the boxes or drawers and wherein provision is made for the proper fitting of the doors.

40 The invention consists in the details of construction and in the combination and arrangement of the several parts of my improved shells for deposit boxes whereby certain important advantages are attained and the device rendered simpler, less expensive and otherwise more convenient and advantageous for use, as will be hereinafter more fully set forth.

The novel features of my invention will 45 hereinafter be definitely claimed.

In order that my invention may be the better understood, I will now proceed to describe the same with reference to the accompanying drawings, wherein:

Figure 1 is a fragmentary view partly in 60 elevation and partly in section of a shell for deposit boxes constructed in accordance with an embodiment of my invention.

Fig. 2 is a vertical transverse sectional view taken through my improved device as 65 herein embodied.

Fig. 3 is a sectional view taken substantially on the line 3—3 of Fig. 1.

Fig. 4 is an enlarged fragmentary sectional view illustrating one form of weld 70 joint.

Fig. 5 is a view similar to Fig. 4 but illustrating a second form of weld joint.

Fig. 6 is a fragmentary view in perspective of my improved device as herein embodied. 75

Fig. 7 is a fragmentary view in perspective showing a vertical sheet and a horizontal sheet in separated relation, and

Fig. 8 is a fragmentary horizontal sectional view showing in detail certain of the supplemental sheets as herein included. 80

As herein embodied my improved shell comprises the side walls 1 and the top and bottom walls 2. The adjacent walls 1 and 2 are connected or united as indicated by 85 3 through the medium of acetylene or electric arc welding, the said connections or joints rounded, although, as illustrated in Fig. 5, said corners may be substantially 90 square and in which instance the coating ends of adjacent walls 1 and 2 are suitably beveled as indicated at 3^a.

The shell or structure provided by the assembled walls 1 and 2 are intersected by 95 the vertically disclosed and equi-distantly spaced sheets 4 which are secured to the upper and lower walls 2 by spot welding as indicated at 5 so that when mounted or assembled within the frame or shell said sheets 100 4 comprise substantially an integral part of the structure.

The forward vertical marginal portions of the sheets 4 and corresponding marginal portions of the side walls 1 are provided 105 with the vertically and equi-distantly spaced open slots or recesses 6 in which are adapted to snugly fit the closed end portions 7 of the slots 8 formed in the horizontally arranged sheets 9 intersecting the shell or frame. The 110

- ends of the sheets 9 at the forward marginal portion thereof are provided with the extensions 10 which snugly engage within the open slots or recesses 6 in the side walls 1.
- 5 The interfitting portions of the sheets 9 and the side walls 1 and the vertical sheets 4 are also welded together so that the sheets 9 will constitute substantially integral parts of the structure.
- 10 The assembled sheets 4 and 9 provide within the shell or frame the nests N each of which is adapted to slidably receive in a conventional manner a deposit box or the like of ordinary construction.
- 15 Spot welded as at 11 to the opposed side walls of each of the nests N are the supplemental plates 12 completely bridging the space between adjacent horizontal sheets 9 or between a sheet 9 and a top or bottom wall 2.
- 20 The supplemental sheets 12 have their front ends terminating inwardly of the front edges of the sheets 4 and 9 so that doors of a common type may be effectively employed in connection with the nests N. As the 25 doors form no part of my present invention a detailed description and illustration thereof is believed to be unnecessary.
- Through the instrumentality of the supplemental plates 12 each of the nests is materially reinforced and strengthened resulting in the desired accuracy in holding the deposit boxes and also assuring the accurate fitting of the doors. In effecting the various 30 joints and connections by welding in place of the old method of dove-tailing at a few points and hand riveting, the resultant structure is of pronounced strength so that in handling the same the nests will not be thrown out of true resulting in the binding 35 of the boxes therein and of the doors.
- 40 B denotes a metallic back plate which is welded to the rear edges of the side walls 1, top and bottom walls 2 and the sheets 4, 9 and 12.
- 45 From the foregoing description, it is thought to be obvious that a shell for deposit boxes constructed in accordance with my invention is particularly well adapted for use by reason of the convenience and facility with which it may be assembled and 50 operated and it will also be obvious that my invention is susceptible of some change and modification without departing from the principles and spirit thereof and for this 55 reason I do not wish to be understood as limiting myself to the precise arrangement and formation of the several parts herein

shown in carrying out my invention in practice except as hereinafter claimed.

I claim:

1. A structure of the class described comprising a frame, vertically disposed sheets intersecting the frame and horizontally spaced, the forward vertical marginal portions of said sheets being provided with open end slots, and horizontally disposed and vertically spaced sheets intersecting the frame and provided with slots whereby the vertically disposed sheets and horizontally disposed sheets interfit to provide nests, the 65 opposed side walls of each of the nests having secured thereto supplemental plates bridging and snugly fitting within the space between the top and bottom walls of the nests.

2. A structure of the class described comprising a frame, vertically disposed sheets intersecting the frame and horizontally spaced, the forward vertical marginal portions of said sheets being provided with open slots, and horizontally disposed and vertically spaced sheets intersecting the frame and provided with slots whereby the vertically disposed sheets and horizontally disposed sheets interfit to provide nests, the 70 opposed side walls of each of the nests having secured thereto supplemental plates bridging and snugly fitting within the space between the top and bottom walls of the nests.

3. A structure of the class described comprising a frame, vertically disposed sheets intersecting the frame and horizontally spaced, the forward vertical marginal portions of said sheets being provided with open end slots, and horizontally disposed and vertically spaced sheets intersecting the frame and provided with slots whereby the vertically disposed sheets and horizontally disposed sheets interfit to provide nests, the 75 opposed side walls of each of the nests having secured thereto supplemental plates bridging and snugly fitting within the space between the top and bottom walls of the nests, the forward ends of the supplemental 80 sheets terminating inwardly of the forward edges of the vertical and horizontal sheets.

3. A structure of the class described comprising a frame, vertically disposed sheets intersecting the frame and horizontally spaced, the forward vertical marginal portions of said sheets being provided with open end slots, and horizontally disposed and vertically spaced sheets intersecting the frame and provided with slots whereby the vertically disposed sheets and horizontally disposed sheets interfit to provide nests, the 85 opposed side walls of each of the nests having secured thereto supplemental plates bridging and snugly fitting within the space between the top and bottom walls of the nests, the forward ends of the supplemental 90 sheets terminating inwardly of the forward edges of the vertical and horizontal sheets.

3. A structure of the class described comprising a frame, vertically disposed sheets intersecting the frame and horizontally spaced, the forward vertical marginal portions of said sheets being provided with open end slots, and horizontally disposed and vertically spaced sheets intersecting the frame and provided with slots whereby the vertically disposed sheets and horizontally disposed sheets interfit to provide nests, the 95 opposed side walls of each of the nests having secured thereto supplemental plates bridging and snugly fitting within the space between the top and bottom walls of the nests, said supplemental sheets being held in position by spot welding.

In testimony whereof I hereunto affix my signature in the presence of two witnesses. 110

FRANK E. VAN DOORN.
